UNITED STATES PATENT OFFICE

BRUNO W. OERTEL, OF PORTLAND, OREGON

DIVING HURDLE

Application filed September 5, 1929. Serial No. 390,524.

My invention relates to athletic devices, and particularly to a device for promoting and teaching skillful diving. It is to be used in connection with swimming pools and other waters of sufficient depth to permit diving. In its entirety it consists of a spring board to give impetus to a vertically directed diving jump, and a vertically adjustable hurdle over which those using the device are required to launch themselves into the water. When performed properly, the diver describes a graceful arc, moving head foremost over the hurdle into the water. The hurdle consists of a horizontally disposed yieldable member located in a vertical plane somewhat forward of the free end of the spring-board. It is supported by two inclined spars projecting over the water, the inclination of which may be altered to permit raising or lowering the hurdle. For those just learning to use the device, the hurdle is placed at its lowermost position, and as the diver gains proficiency, the hurdle is raised so that it will constantly test the diver's skill in clearing it. In addition thereto the spring-board is adjustable, to allow for varying weights of those using it. In other words, one adjustment of the spring-board allows of its use by women and children, while another allows of its use by men with equal results. From the foregoing it will be seen that my invention has several objects.

One object is to provide a spring board adjustable as to springiness.

Another object is to provide a vertically adjustable hurdle for use with said spring board.

A further object is to provide in such a hurdle, construction which will limit if not entirely obviate danger of accidents.

Other objects will become apparent upon reading the description following, aided by the drawings accompanying the same, wherein

- 45 Figure 1 is a plan view of my invention;
- Fig. 2 is a front elevation;
- Fig. 3 is a side elevation;
- Fig. 4 is a detached view partly in section of a safety pulley used with my invention;
- 50 Fig. 5 is a fragmentary detail of a support;

Fig. 6 is a perspective of a spring board adjusting wedge;

Fig. 7 is a side elevation of a spring board support;

Fig. 8 is a view similar to Fig. 7; and

Fig. 9 is a side elevation of the spring board used in my invention.

Similar numerals refer to similar parts throughout the several views:

In the drawings 1 represents a foundation for my invention, which may be a dock, a support especially constructed therefor, a float, or any manner of a support found suitable therefor, which faces the water 2. For the purposes of this description, the member 1 will be called a dock, and on it is provided a support for the spring-board 3. The spring-board support includes an elongated member or beam 4, blocks 5 and 6 and wedge 7. A holding bolt 8 passes through the board 3, and the blocks 5 and 6, and into the dock, and a like bolt 9 passes through the board 3 and the beam 4 into the dock. These bolts secure the stationary end of the board to the supporting elements just described and to the dock. There is a little play between the upper block 6 and the lower block 5 to allow the insertion of the wedge 7 between the two blocks as in Fig. 8, or between the upper block and board 3 as shown in Fig. 7. Wedge 7 is provided with an elongated slot 10 which allows it to pass about the bolt 8. The purpose of the first position of the wedge is to adjust the board for women and children, and the second, for heavier persons. The stationary end of the board 3 is provided with two plates 11 and 12, through the first of which the bolt 8 passes and through the second, the bolt 9 passes. These are provided to prevent the bolts splitting board 3.

The spring-board 3 is a two-ply member consisting of two tapered units 13 and 14. The unit 14 is the spring member and may be made of wood suitable for that purpose, such as spruce. The upper unit 13 is of a wood suitable for giving a foothold, such as cotton-wood, and is intended to avoid the use of rubber mats and the like. The two units 13 and 14 are held together by a suitable waterproof cement. The board 3 is of sufficient

length to extend substantially over the water 2.

Two base plates 15 and 16, each have one end fastened by bolts or studs 17 to the beam 4, and their other ends directed toward each other and fastened by the same means to the dock 1. Each base 15 and 16 is provided with a number of openings therethrough or sockets 18, the purpose of which will be referred to hereafter.

Two upright members or vertical supports 19 and 20, one of which is spaced from and at one side of the board 3, and the other in a similar position at the other side, each have a bifurcated upper end 21 providing a slot or cradle 22 to receive the spars 23 and 24. The uprights 19 and 20 are of course situated proximate the edge of the dock 1. The bifurcated ends 21 have inclined pin holes 25 for the pins 26, which pins are utilized for supporting the spars at different elevations within the cradles 22.

The purpose of the uprights 19 and 20 is to provide a support for the inclined spars 23 and 24 so that their elevated ends 27 may project substantially over the water 2. The ends 27 are in a vertical plane situated at a substantial distance beyond the end 28 of the spring-board 3. It is the purpose of the supporting apparatus heretofore described, to permit the ends 27 of the spars to be elevated or depressed, at the same time maintaining them in substantially the same vertical plane with regard to parallelity with the dock 1. The base ends 29 of the spars always rest in corresponding sockets 18 in the base plates 15 and 16. When the spars are raised by means of the pin 26, the ends 29 of the spars are inserted in sockets 18 remote from beam 4, and when the spars are lowered, the ends are inserted in corresponding sockets proximate the beam 4. When the spars are raised and the ends rest in the sockets remote from beam 4, ends 27 spread apart, and when the spars are lowered and the ends rest in the sockets proximate the beam 4, the ends 27 are closer together, thus aiding in maintaining the ends 27 in substantially one vertical plane. This is shown by the position of the ends 27A of the outlines 23A and 24A of the spars 23 and 24. At the respective ends 27 of the spars are swivelly attached grooved pulleys 30 through which passes rope 31. The rope 31 is of substantial length and endless (though its entirety is not shown in the drawings).

The rope 31 has two portions, a short portion 31A and a long portion 31B. The long portion 31B of the rope 31 hangs down into the water and acts as a weight for maintaining the short portion 31A in a fairly horizontal position. The portion 31A forms the hurdle over which persons dive from the spring-board 3. If through miscalculation the diver should fall upon the rope portion

31A, it will easily give away, and the long portion has sufficient length to avoid being drawn up and striking him. As a further safeguard, the pulleys 30 are so constructed that they become detached from their spars when an unusual amount of weight is carried, as for example ten pounds over normal. To accomplish this the pulley 30 is provided with a U-shaped frame 32 within which it is free to revolve upon the cone-shaped bearings 34 of the frame projecting into corresponding recesses in the hub of the pulley 30. The foregoing construction allows the pulley to be withdrawn from the frame, the force exerted for that purpose, of course, being regulated by the stiffness of the frame. The frame is provided with a swivel hanger 33 by which it is connected to its spar.

Having described my invention, what I claim as new and desire to protect by Letters Patent, is:—

1. A pair of upright members, said upright members each having a bifurcated upper end to provide a cradle, the bifurcated portion of each upright being provided with a plurality of vertically spaced inclined pin holes, an inclined spar carried within each cradle, a pin extending through one of the aforesaid inclined holes supporting said spar, and a flexible member extending in a substantially horizontal manner between the upper ends of said spars.

2. A pair of upright members, said upright members each having a bifurcated upper end to provide a cradle, the bifurcated portion of each upright being provided with a plurality of vertically spaced inclined pin holes, a pin extending through a selected one of said pin holes supporting a spar, a base plate for each spar, each base plate being provided with a plurality of sockets within one of which rests the lower end of the spar, and the sockets of one base plate being arranged relative to the sockets of the other to afford means for regulating the distance between the upper ends of said spars.

3. A pair of upright members, said upright members each having a bifurcated upper end to provide a cradle, the bifurcated portion of each upright being provided with a plurality of vertically spaced pin holes, a pin extending through a selected one of said pin holes supporting a spar, a base plate for each spar, each base plate being provided with a plurality of sockets within one of which rests the lower end of the spar, the sockets of one base plate being arranged relative to the sockets of the other to afford means for regulating the distance between the upper ends of said spars, and a flexible member extending in a substantially horizontal manner between the upper ends of the aforesaid spars.

4. A pair of upright members, said upright members each having a bifurcated upper end

to provide a cradle, an inclined spar carried in each cradle, a flexible member extending in a substantially horizontal manner between the upper ends of said spars, and a base for each spar having sockets to receive the lower end of said spar.

5. A pair of upright members, said upright members each having a bifurcated upper end to provide a cradle, an inclined spar carried in each cradle, a frame swivelled to the upper end of each spar, a pulley removably clasped by said frame, an endless rope passing over said pulleys, said rope being arranged to provide a substantially horizontal portion suspended between the aforesaid pulleys, and a base for each spar having sockets to receive the lower end thereof.

6. A pair of upright members, said upright members each having a bifurcated upper end to provide a cradle, an inclined spar carried in each cradle, a frame swivelled to the upper end of each spar, a pulley removably clasped by said frame, an endless rope passing over said pulleys, said rope being arranged to provide a substantially horizontal portion suspended between the aforesaid pulleys, a base for each spar having sockets to receive the lower end thereof, and the sockets of one base being arranged relative to the sockets of the other to afford means for regulating the distance between the upper ends of said spars.
